UNITED STATES PATENT OFFICE

159,059

TEXTILE FABRIC

Chester K. Goldberg, Phoenix, Ariz.

Application November 15, 1949, Serial No. 6,049

Term of patent 3½ years

(Cl. D92—1)

To all whom it may concern:

Be it known that I, Chester K. Goldberg, a citizen of the United States, residing at Phoenix, county of Maricopa, and State of Arizona, have invented a new, original, and ornamental Design for a Textile Fabric, of which the following is a specification, reference being had to the accompanying drawing, forming part thereof, and wherein the figure on the drawing is a plan view of a textile fabric, showing my new design.

The dot and dash lines on the drawing outline a design unit, which unit is repeated in regular succession as indicated by the extensions beyond the unit boundaries.

I claim:

The ornamental design for a textile fabric, as shown and described.

CHESTER K. GOLDBERG.
